The ornamental design for a spunbond polypropylene disposable hat, as shown and described.

DESCRIPTION

FIG. 1 is a side perspective view of the spunbond polypropylene disposable hat embodying the design of the present invention;

FIG. 2 is a top down view of the design of FIG. 1 disassembled, unfolded and laid flat;

FIG. 3 is a rear view of the design of FIG. 1 showing the two parts of the spunbond polypropylene disposable hat partially assembled.

FIG. 4 is a front view of the design of FIG. 1;

FIG. 5 is a rear view thereof;

FIG. 6 is a left side view thereof;

FIG. 7 is a right side view thereof;

FIG. 8 is a top down view thereof;

FIG. 9 is a bottom plan view thereof;

FIG. 10 is a cross-sectional view taken along line 10-10 of FIG. 8; and,

FIG. 11 is an enlarged detail view of area 11 circumscribed within FIG. 10, showing the stitching thereof.

The dot-dash-dot broken lines circumscribing the areas of the details in FIGS. 10 and 11 form no part of the claimed design. The dash-dash broken lines depict stitching elements.
